UNITED STATES PATENT OFFICE.

WILLIAM S. KELLOGG, JR., OF PEORIA, ILLINOIS.

CARBURETER.

1,144,477.

Specification of Letters Patent. Patented June 29, 1915.

Application filed July 10, 1911. Serial No. 637,811.

To all whom it may concern:

Be it known that I, WILLIAM S. KELLOGG, Jr., a citizen of the United States, residing at Peoria, in the county of Peoria and 5 State of Illinois, have invented certain new and useful Improvements in Carbureters, of which the following is a specification.

My invention relates to carbureters.

The object of my invention is to provide 10 a carbureter operating wholly under the influence of a current induced by the engine to apply a uniform quality of mixture without regard to the speed at which the engine is run.

Another object of my invention is to provide 15 means for controlling the mixture of air and the liquid base to produce the desired mixture.

My invention consists in the provision of 20 a combined float and carbureting chamber, means for raising the liquid base to the induced current through the carbureting chamber, means for controlling the liquid exposure to the air current and for mixing 25 the same, and other details of construction hereinafter more particularly described.

Referring to the drawings—Figure 1 is a side elevation showing the general form of the device; Fig. 2 is a vertical sectional view on the line 2—2 of Fig. 1; Fig. 3 is a side elevation with parts broken away to show interior construction; Fig. 4 is a top view on the line 4—4 of Fig. 1; Fig. 5 shows one form of a templet, and Fig. 6 shows another form of a templet.

Referring to the figures, A refers generally to a combined float and carbureting chamber formed of two sections 2 and 3 adapted to be joined together in any suitable manner to render the joint therebetween perfectly air and gas tight. The liquid fuel base is designed to be carried in the lower portion of section 2 and the flow of liquid into said section is controlled 45 by float 4 in the usual well known manner.

5 is an air inlet into the carbureting portion of the carbureter and 6 is a mixture outlet adapted to communicate with the engine, the air inlet and mixture outlet being 50 preferably arranged in different horizontal planes.

7 is a disk adapted to be arranged within the combined float and carbureting chamber in substantially the relation shown.

55 7^a are perforations through the body of the disk which I have shown as angularly

disposed with relation to the air inlet and mixture outlet or both.

8 is a spindle to which disk 7 is fixed and which is provided at its ends with cone points 9, the respective ends adapted to be supported in cone bearings in set screws 10 and 11, the latter being carried in suitable threaded openings in the body of the chamber in substantially the relation shown.

60 The mixture outlet is controlled by butterfly valve 12 which is supported on suitable spindles journaled in the walls at the mouth of the opening out of the carbureting chamber, the movement of said valve 65 being adapted to be controlled by the operator through crank arm 13 fixed upon butterfly valve spindle.

70 In the operation of my device I have found it desirable to provide a brake against excessive speed of disk 7. To this end I have provided the auxiliary disk 14 fixed upon spindle 8, a sectional push rod 15 and the interposed spring 16. This push rod and interposed spring are carried in a 75 perforation through a cast extension 17 from the wall of chamber 2.

80 18 refers generally to a templet portion of a brake arm connected through cast part 22 with crank arm 19, said templet being 85 preferably formed as shown in either Figs. 2, 5 or 6 according to the associated use with different engines, in which figures the face 20 is formed straight and the face 21 cam shaped. The cast portion 22 of the complete 90

brake arm is adapted to be fixed in an adjustable relation in connection with crank arm 19 within slot 23, substantially as shown in Fig. 1. The lower portion of arm 18 is adapted to depend through slot 24 in cast 95 extension 17 and the face 20 of said arm has normally a bearing relation with push rod 15. The initial position of arm 18 with relation to push rod 15 is adapted to be fixed by means of set screw 25 substantially 100 as shown in Fig. 2. The form of the cam face portion 21 of the brake arm 18 will vary under varying conditions of use. This variation can be determined only by test; and is accomplished by first setting the arm 105 with relation to the screw 25 and push rod 15 to proper working condition on low speed. Then the valve is opened step by step with the increase of speed. Then by a

series of tests to determine the adjustment 110 at points intermediate the extremities of the templet, the required variation of distance.

2
between the faces 20 and 21 of said templet will be also determined. Commonly, if not uniformly, the most abrupt braking effect will occur at the beginning of the opening of the butterfly valve and thereafter the increased braking effect required will be ordinarily very gradual up to the point of the complete opening of said valve.

The form of the float chamber and carbureting chamber, and in fact the combined structure that forms said chamber may be varied to suit the requirements of use except that they shall be in communicating relation. The air inlet and mixture outlet openings likewise may be modified to accommodate varying conditions of use. The brake mechanism adapted to control the speed of disk 7 may be in any suitable form to accomplish the purpose, for instance, the construction may be such that push rod 15 may have a direct bearing upon the face of disk 7.

I have shown in the drawings a brake mechanism adapted to control the speed of wheel 7. However, under certain conditions of use this brake mechanism may be dispensed with entirely. For instance, a carburetor may be associated with engines of a certain uniform and defined structure. In such case the combined area of the perforations in disk 7 and that of the air inlet may be so proportioned that the disk wheel will be automatically controlled and its speed confined within limits consistent with the working combination in which it is used, to produce a uniform quality of mixture throughout the variations of speed at which the engine is run. The brake mechanism is provided merely to render a single carburetor adaptable for use in connection with any engine.

In operation, the parts having been adjusted in the relative positions shown in the drawings, the initial starting of the engine having been accomplished and the butterfly valve 12 opened, as the pistons of the engine are reciprocated, a current of air is induced through air inlet 5, perforations 7^a of the disk wheel 7 and through mixture outlet 6, and from thence into the engine cylinder. The action of the air being drawn through openings 7^a will cause disk 7 to be rotated, serving to raise the liquid base into contact with the air passing through the carbureting chamber and as it is thinly spread upon the surface of the disk and upon the walls of the perforations, it is readily taken up by the air, and as almost every particle of air passing through the chamber is brought into contact with liquid in condition for ready vaporization, a perfectly natural mixing occurs that renders the mixture perfect without auxiliary mixing means, at least in the ordinarily low or moderate speeds of the engine. As the speed of the engine in-

creases the speed of rotation of disk 7 will be proportionately increased, serving to equalize the exposure of liquid to the air current in proportion to the increased flow of air through the carbureting chamber, thus insuring a proportionate mixture of the two basic elements of the mixture that will effect a constant uniformity of mixture. The flow of mixture into the engine is always under control of the operator through 75 and by proper manipulation of the butterfly valve, as is well understood.

As previously stated, if the combined area of perforations 7^a in disk 7 is properly proportioned to the size of the air inlet, no control mechanism is needed to limit the speed of said disk. However, as also previously stated, in order to meet the varying conditions of use of a carburetor with any engine, a control may be found necessary.

85
The operation of the control mechanism is as follows: The proper adjustment of brake arm 18 having been made with relation to push rod 15, the opening of the butterfly valve to admit an increased flow 90 of air with an accompanying increase in the speed of the engine would result in an increased speed of disk 7. Because of the disk having a free support upon its bearing, this would result normally in a proportionately 95 greater speed of said disk than that of the increased flow of air therethrough. To check this normal tendency to greater proportionate speed, the brake mechanism is connected up with butterfly valve 12 so that 100 as it is opened the brake arm 18 is depressed, and being in bearing relation with push rod 15 pushes the latter into frictional brake contact with auxiliary disk 14. The form of the brake arm is such that with the increased 105 opening of the butterfly valve there will be exerted a greater brake force applied to auxiliary disk 14, such proportionate brake force being adapted to be such as to confine the speed of disk 7 within a certain defined 110 limit so as to prevent too great an agitation of the liquid within the carbureting chamber.

115
It may be that other mechanical means might be employed to raise the mixture base to the current passing through the carbureting chamber and to agitate the same within certain practical limits, and it may be that the relative positions of the air inlet and mixture outlet may be such to perforations 120 in the disk that substantially straight perforations at right angles with the faces of the disk may be employed and still induce the desired rotation therein, therefore I do not wish to confine myself to the particular 125 detail structure which I have herein shown and described, but it is my desire that it shall comprehend any and all forms of embodiment of my invention that fall legitimately within the principle thereof.

What I claim is:—

1. A carbureter comprising a communicating float and carbureting chamber, the latter provided with an air inlet and a mixture outlet, and a rotatable member interposed between the air inlet and the mixture outlet turnable within both chambers provided with perforations tangentially disposed with relation to an induced current passing through the carbureting chamber. 5
2. A carbureter comprising a combined float and carbureting chamber, the latter provided with an air inlet and a mixture outlet, a valve control for the mixture outlet and a disk rotatable in the float and carbureting chamber provided with perforations tangentially disposed with relation to an induced air current passing through the carbureting chamber. 15
3. A carbureter comprising a combined float and carbureting chamber, an air inlet and a mixture outlet, and a suctionally operated disk interposed between the air inlet and mixture outlet openings provided with 25 perforations tangentially disposed with relation to the induced current passing through the carbureting chamber.
4. A carbureter comprising a carbureting chamber, an air inlet and mixture outlet and a perforated disk disposed between the inlet and outlet actuated by an air current induced from the engine cylinder passing through the disk, a valve for controlling the outflow of air, and means actuating in conjunction with said valve to apply brake pressure to the disk. 35
5. A carbureter comprising a combined float and carbureting chamber, the latter provided with an air inlet and mixture outlet, means for controlling the mixture outlet and a suctionally rotatable disk interposed between the air inlet and mixture outlet provided with a plurality of perforations angularly disposed with relation to the direction of flow of the induced current through the carbureting chamber, the combined area of said perforations being as great at least as the area of the air inlet. 45
6. A carbureter comprising a combined float and carbureting chamber, the latter provided with an air inlet and a mixture outlet, a valve control for the latter, a rotatable disk disposed between the air inlet and mixture outlet forming substantially a closed wall therebetween and provided with a plurality of perforations so angularly disposed with relation to the direction of flow of the air passing through the carbureting chamber that the disk will be rotated to cause it to travel in the liquid in the float chamber to carry said liquid to exposure with the air current passing through the carbureting chamber and under rapid rotation to agitate and spray the liquid therein. 55
7. A carbureter comprising a float chamber, a carbureting chamber above the float chamber provided with an air inlet and a mixture outlet, and means movable by the suction from the engine cylinder interposed between said air inlet and mixture outlet comprehending in its travel a passage from the float chamber to the carbureting chamber to carry the liquid to be carbureted to exposure with the air current passing through the carbureting chamber, a valve for controlling the outflow of air, and means actuating in conjunction with said valve to apply brake pressure to the disk. 70
8. A carbureter comprising a float chamber, a carbureting chamber over the float chamber provided with an air inlet and a mixture outlet and a rotatable member interposed between the air inlet and mixture outlet, suctionally operated from the engine cylinder, a valve for controlling the outflow of air, and means actuating in conjunction with said valve to apply brake pressure to the disk. 75
9. A carbureter comprising a float chamber, a carbureting chamber provided with an air inlet and a mixture outlet, rotatable means between the air inlet and mixture outlet comprehending in its travel a passage through both chambers adapted to carry the liquid to be carbureted to exposure with the air current passing through the carbureting chamber, provided with openings therethrough tangentially disposed with relation to the direction of flow of air through the carbureting chamber. 80
10. A carbureter comprising a float chamber and a carbureting chamber, the latter provided with an air inlet and a mixture outlet, a valve for controlling the mixture outlet opening, a suctionally rotatable member interposed between the air inlet and the mixture outlet provided with openings therethrough angularly disposed with relation to the direction of flow of the air through the carbureting chamber, and means under the control of the operator for controlling the speed of the disk. 85
11. A carbureter comprising a float chamber, a carbureting chamber provided with an air inlet and a mixture outlet, control means for the mixture outlet and means interposed between the air inlet and the mixture outlet movable by the air current induced from the engine cylinder for the purpose of raising the mixture base to the air current in proportionate quantities to meet the requirements of the varying flow of air therethrough to produce the proper mixture under the varying speed of the engine, a valve for controlling the outflow of air, and means actuating in conjunction with said valve to apply brake pressure to the disk. 90
12. A carbureter comprising a float chamber, a carbureting chamber provided with 105
13. 110
14. 115
15. 120
16. 125
17. 130

an air inlet and a mixture outlet, control means for the mixture outlet, means interposed between the air inlet and the mixture outlet movable by the air current passing through the carbureting chamber for the purpose of raising the mixture base to the air current in proportionate quantities to meet the requirements of the varying flow of air therethrough to produce the proper mixture under the varying speed of the engine, and manually operated means for controlling the movement of said movable means.

13. A carbureter comprising a float chamber and carbureting chamber provided with an air inlet and mixture outlet, a disk rotatable by an induced current of air passing through the carbureting chamber provided with a plurality of perforations tangentially disposed with relation to the direction of flow of air to the disk and a manually controlled means comprising a sectional push rod adapted for connected brake relation with the disk, and a resilient member

interposed between the sections, a crank arm, a brake arm substantially as shown adjustable with relation thereto, and means for adjusting the complete arm with relation to the push rod.

14. A carbureter comprising a float chamber, a carbureting chamber provided with an air inlet and mixture outlet, a disk rotatable by an induced current of air passing through the carbureting chamber provided with a plurality of perforations tangentially disposed with relation to the direction of flow of the air to the disk, and manually controlled means for controlling the speed of the disk comprising a push rod having a brake relation with said disk, a brake arm and a crank arm connected therewith.

In testimony whereof I have affixed my signature in presence of two witnesses.
